(57) CLAIM

The ornamental design for a combined audio player and recorder, as shown and described.

DESCRIPTION

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.

FIG. 1 is a perspective view of a combined audio player and recorder, showing my new design;

FIG. 2 is a first side elevation view thereof;

FIG. 3 is a top plan view thereof;

FIG. 4 is a bottom plan view thereof;

FIG. 5 is a second side elevation view thereof;

FIG. 6 is a third side elevation view thereof; and,

FIG. 7 is a fourth side elevation view thereof.

The broken line portions of FIGS. 1, 4, 6 and 7 are included to show unclaimed subject matter, only, and form no part of the claimed design.
